INVENTOR

Carter D. Knowlton
By his Attorney,
Nelson M. Howard

UNITED STATES PATENT OFFICE

CUTLER D. KNOWLTON, OF BEVERLY, MASSACHUSETTS, ASSIGNOR TO HOAGUE-SPRAGUE CORPORATION, OF LYNN, MASSACHUSETTS, A CORPORATION OF MASSACHUSETTS

BOX AND BLANK THEREFOR

Original application filed August 29, 1927, Serial No. 216,220. Divided and this application filed February 10, 1930. Serial No. 427,206.

This invention relates to boxes and blanks from which said boxes are made, being specially concerned with the formation of a smooth, finished edge where the box-material is divided, as at the corners of the box, and with the strengthening of such corners. The present application is a division of that filed in the United States Patent Office in my name on August 29, 1927, with the 10 Serial No. 216,220, this original application being directed to making the herein disclosed boxes and blanks. Said application, on June 16, 1931, became Letters Patent No. 1,821,307.

When boxes of the type disclosed in Patent No. 1,476,549, Smith, December 4, 1923, and consisting of a pasteboard shell covered with paper, are produced by assembling the shell-material and cover-material before the 20 boxes are set up, there are left exposed, unless precautions are taken to hide them, unsightly strips of shell-material. This may occur, for example, at the vertical edges of the wings which overlie the corner-laps 25 at the ends of the boxes. An object of the invention is to attain an effective concealment of the shell-edges, providing to this end a novel box-blank and box. In the blank, the sheet from which it is to be formed, which may be shell-material with cover-material attached to one of its faces, has cuts which extend partly through from 30 opposite sides in proximity to creases separating the areas which are to furnish the 35 box-walls, as those creases defining the corner-laps. The cuts are herein shown as on opposite sides of such creases. The shell-material is divided in a plane joining the bottoms of the cuts, this plane being preferably parallel to the outer faces of the sheet and within the shell-material. There 40 is thus furnished a reduced extension which is to be secured to an adjacent surface. In the preferred box-organization, this adjacent surface is upon the extension itself, it being folded inwardly in a novel manner, and appearing as secured to a separate box-element. This element may be a corner-lap, while the extension is a part of an end wing. 45 Upon this extension, the cover-material is

exposed at the folded-over edge and the raw edge of the shell entirely concealed.

In the accompanying drawings,

Figs. 1 and 2 suggest, diagrammatically and in perspective, apparatus by which my improved blanks and boxes may be produced, the blank appearing at the right of Fig. 2;

Fig. 3 is an enlarged transverse section through the scoring mechanism of the apparatus;

Fig. 4 is an enlarged longitudinal section through the splitting mechanism;

Fig. 5 shows the forming mechanism in its initial position;

Fig. 6 is a perspective view of a portion 65 of a box made from the blank of this invention; and

Fig. 7 is a similar view of the box of such invention.

When here and elsewhere in the specification a box is referred to, it is to be understood that the invention applies as well to box-covers as to the bodies.

In making the box of Fig. 6 by a continuous-production method, I prefer, though it 75 is not essential to the invention, to advance a web of pasteboard A or other material suitable for the box-shell, this web being mounted upon a spindle 10, while adjacent to it a web of such cover-material B as paper 80 is arranged to turn upon a spindle 12. Glue or other appropriate adhesive is applied to the inner face of one of the webs, as B, by a device 14, after which said webs are assembled by being pressed together and are advanced by a pair of rolls 16, 16. The cover-web may be somewhat wider than the shell-web and is shown as turned over at *a* and forced against the under side of the shell, which is at the inside of the box, by opposite folding abutments 18, but one of which is shown. By a mechanism 20 the assembly is provided with longitudinal creases *b*, *b*, which mark the junctures of the box-bottoms *c* and side wings *d* and between the end 95 wings *e* and the corner-laps *f*. A mechanism 22 creases the assembly transversely at *g*, thus defining the successive lines between the bottoms *c* and end wings *e* and between the side wings *d* and the corner-laps *f*. By a 100

roll mechanism 24 each box-section of the assembly is scored at its opposite sides. At the lower or shell-side, arcuate knives 26, 26 carried by the under roll of the pair cut lines *h* (Fig. 3), preferably substantially coinciding with the crease-lines *b* and extending along the junctures between the end wings and corner-laps of adjacent sections. At the same time, the upper or cover-paper side is scored by circumferential knives 28, 28 somewhat separated from the knives 26 transversely of the sheet. The lines *i*, *i* thus cut are spaced outwardly from the lines *h*, to which they are parallel. At their adjacent ends, each line *i* is joined to the vertical plane through the companion line *h* by an inclined line *j* which is scored in the material by a knife 30. At its opposite or outer end, each line *i* is shorter than the corresponding line *h*, and here an inclined score-line *k* connects the lines *i* and *h*, being produced by a knife 32. The lines *j* and *k* which are on the same corner-lap cover outwardly to the line *i* which connects them. The bottoms of all these scores terminate in a common plane *l* parallel to the outer faces of the sheet. This plane may be located at about one-third of the distance through the assembly from the cover-paper side. As will hereafter appear more clearly, there may be conditions which call for a change in the relation between the depths of the scores. After being scored, the assembly is acted upon by cutting mechanism 34, which divides it into individual box-blanks C, the separation occurring along transverse lines *m* passing through the junctures of the scores *j*. The partially completed blanks thus divided are shown as accumulated in a stack within a receiver 36.

The blanks may now have the corner-laps separated from the end wings to which they are connected, at the same time there being a marginal extension of reduced thickness created upon each extremity of the end wing. A means for effecting this is illustrated in connection with the setting-up apparatus of Fig. 2. The blanks, in a direction at right angles to that which they followed in the assembling operation, are advanced between opposite pairs of rotatable rolls 38 and 40. Each roll 38 has a pair of projections 42, so arranged that in connection with a registering depression in the corresponding bed-roll 40 it will act to force apart one of the corner-laps and connected end wing in a direction substantially at right angles to the plane of the blank. The force applied in this direction causes the material to tear, first along the score *j* and the outer extremity of the score *h*, then upon the lines *h* and *i*, and finally upon the line *k* to the termination of the line *h*. Throughout this division, the pasteboard splits in substantially the plane *l* common to the edges of the knives 26, 28,

30 and 32, and therefore to the bottoms of the scores which they produce. The inclination of the scores *j* and *k* at the beginning and end of each divided area reduces the tendency of the division or tear to leave the scored lines and mutilate the cover-paper upon the marginal extension. The division of each corner-lap from the end wing at each side of the blank may be completed by a curved deflecting rail 44, beneath which the corner-lap passes while the roll-projection 42 is still pressing it down. There is thus produced upon each extremity of each end wing a comparatively thin extension or flap *n*, its outer face completely covered with paper, within which is a substantial thickness of shell-material with its inner face approximately parallel to the paper. On the associated corner-lap there is a similar extension *r*, which, in the present instance, is thicker than *n*. The rails 44 bring the corner-laps to positions substantially at right angles to the remainder of the blank, and there retain them while each end wing, upon its under or shell-side, is acted upon by a gluing mechanism 46 which coats the surface, including the extensions. From the gluing mechanism the blank is carried upon a vertically reciprocating form 48 of a setting-up mechanism 50. The form rises, with the blank upon it, between opposite abutments 52, 52, which turn down the side wings *d* to vertical positions, at the same time carrying the corner-laps across the ends of the form. Then horizontally reciprocating plungers 54, 54 act, upon further elevation of the form, to fold the end wings at the creases *g* and to press their glued faces against the corner laps. At the same time, the coated extensions *n* are forced into engagement with the adjacent surfaces of the side wings through the agency of flanges 56 at each side of each plunger. This completes the formation from the blank C of a box D. One extremity of this box is shown in Fig. 6.

My invention preferably assumes the form illustrated in Fig. 7. Here we have the same general box-structure D as it is in Fig. 6, but the end-wing extension *o* is made of substantially half the thickness of the assembly and after gluing is doubled upon itself within the recess which has been formed, to lie with its face flush with the inner surface of the wall carrying it and secured in this position before the end wing, including the inner folded-over portions is attached to the corner-laps. The inner end of the extension is shown as abutting against the shoulder formed between said extension and the body of the shell-material. Such an arrangement provides an end wing with its vertical edges fully finished, with only rounded surfaces of cover-paper exposed, and also giving a uniform thickness of the

wing, so that its surface is smooth throughout. The corner-lap-extensions *r* lie along the lower edges of the end walls, performing no special function.

5 Having described my invention, what I claim as new and desire to secure by Letters Patent of the United States is:

1. A box comprising walls including shell-material, there being an extension formed 10 solely from the material of one wall and including a reduced portion of the shell-material of substantially uniform thickness, said extension being folded upon itself along substantially the entire length of the wall 15 to which it is joined and secured in this position.

2. A box comprising walls including shell-material and cover-material, there being an extension from a wall including the cover-20 material and a reduced portion of the shell-material of substantially uniform thickness, said extension being folded upon itself and secured in this position and to an adjacent surface with the cover-material exposed at 25 the edge of the fold.

3. A box comprising walls including shell-material, there being at one edge of a wall a portion of the shell-material thinner than the body thereof to produce a recess, said 30 thinner portion being folded upon itself into the recess and secured in this position and to an adjacent wall of the box.

4. A box comprising walls including shell-material, there being at one edge of a wall 35 a portion of the shell-material equal in thickness to approximately one-half the body thereof, said portion being folded inwardly upon itself and adhesively secured with its face substantially flush with the inner face of 40 the wall which carries it.

5. A box comprising shell-material furnishing side wings, corner-laps projecting therefrom, end wings and extensions from the end wings including shell-material of 45 less thickness than the body of the wings, said extensions being secured to the corner-laps and reaching from the bottom of the box adjacent to the top of said corner-laps.

6. A box comprising walls including shell-50 material and cover-material, there being an extension from a wall including the cover-material and a reduced portion of the shell-material of substantially uniform thickness, said extension being folded upon itself and 55 having the cover-material secured to an adjacent surface with the rounded portion

formed by the fold exposed at the exterior of the box along the edge of the wall.

7. A box comprising side wings, corner-laps projecting therefrom, end wings, the side wings and corner-laps including shell-70 material, extensions from the end wings, each extension having its inner face furnished by a surface of the shell-material substantially parallel to the outer face and spaced therefrom by a distance approximately equal to one-half the thickness of the body of the shell-material, and the inner faces of the extensions being folded and secured to themselves and to the corner-laps. 75

8. A box-blank comprising a sheet of box-material having creases separating the areas which are to furnish the box-walls and corner-laps, there being cuts at its opposite faces extending partly through the sheet 80 at opposite sides of the corner-lap-creases, said sheet being divided substantially in a plane joining the bottoms of the cuts to furnish surfaces opposed in the blank.

9. A box-blank comprising a sheet of box-90 material having corner-laps defined by creases having at its opposite faces cuts extending adjacent to the corner-lap-creases and partly through the sheet, one of said cuts having at its extremities cuts extending to 95 the opposite cut.

10. A box-blank comprising a sheet of shell-material having attached to one of its faces a sheet of cover-material and having corner-laps defined by creases, with a cut 100 extending through the cover-material and partly through the shell-material, and a cut extending partly through the shell-material from the side opposite the cover-material, the cuts lying adjacent to the corner-lap 105 creases, the shell-material being divided substantially in a plane joining the bottoms of the cuts to furnish opposed surfaces.

11. A box-blank comprising a bottom-portion, side wings projecting from the bottom-portion and having corner-laps, end wings projecting from the bottom-portion, there being creases between the end wings and corner-laps, scores extending along said 110 creases, and a score adjacent to each of the crease-scores, the blank-material being divided between each of the pairs of adjacent-scores to separate the end wings and corner-laps and to provide reduced margins. 115
